UNITED STATES PATENT OFFICE.

JOHN A. HULT, OF CLEVELAND, OHIO, ASSIGNOR TO THE AMERICAN MULTIGRAPH COMPANY, OF CLEVELAND, OHIO, A CORPORATION OF OHIO.

PAPER DETECTOR FOR PRINTING MACHINES.

Application filed May 20, 1926. Serial No. 110,432.

This invention is concerned particularly with a paper detecting device suitable for use on a rotary printing machine and adapted to prevent the platen being active when 5 paper is absent. The invention is well adapted for embodiment in a rotary addressing machine of the type shown in application No. 100,224 filed April 7th, 1926 by John A. Hult. In that machine there is 10 a rotary drum carrying a body form for printing a circular letter and also a changeable address form, the body form and address form cooperating with one platen to print an addressed letter and the address 15 form alone cooperating with a separate platen to print the address on an envelope. When embodied in such machine, the mechanism of this invention prevents the envelope platen acting except when an envelope 20 is present, the action occurring at the time the address plate is in proper position relative to the envelope platen to print only the address. Such embodiment of the invention is illustrated in the drawings hereof and is 25 hereinafter more fully described.

In the drawings, Fig. 1 is a rear elevation of a rotary addressing machine of the type referred to, equipped with this invention; Fig. 2 is a vertical transverse section 30 thereof, as indicated by the line 2—2 on Fig. 1; Fig. 3 is an approximately horizontal section of a portion of the machine, as indicated by the offset line 3—3 on Fig. 2; Fig. 4 is a vertical transverse section on the 35 line 4—4 on Fig. 1 looking in the opposite direction to Fig. 2; Fig. 5 is a prospective of the envelope pocket and adjacent portions of the detecting device.

I will first describe briefly the general 40 nature of the printing machine shown, and then my detecting mechanism which operates with such printing machine and causes the normally idle platen to become active only if an envelope is present.

As shown in the drawings, the printing machine proper is of the type of the multigraph and comprises a rotary drum 10 mounted on a shaft 11, journalled in end frame plates 12 and 13 above a roller platen 50 14 mounted on a shaft 15. Gearing 16 and 17 and an Oldham coupling partly indicated at 18, connect the drum and platen. Any

suitable means, as for example a crank 19, is provided for rotating the drum and platen.

55

I have shown mounted on the drum a means for printing the body of a form letter, such means comprising a blanket 20 (indicated conventionally in Fig. 2 and a portion of which is shown in Fig. 1) stretched about a segmental portion of the drum and having raised overhanging projections 22 carrying embossed printing strips 23. The segment is shown as a semicylinder resting on the end members 28 and 29 of the drum 60 and held in place by a spring hook 24 engaging the shaft 11. An inking ribbon 25 has its ends wound on spools carried between the end members of the drum, such ribbon extending intermediately about the 70 type form. One of these spools is shown at 27 in Fig. 1.

65

It will be seen that in the construction described, when the drum is rotated, as by means of the crank, paper fed between the 75 drum and platen may be printed by the type characters through the ribbon. The paper may be fed by hand or in some automatic manner as desired.

75

The body of the drum adjacent one edge 80 of the segment 10 is shown in Fig. 2 as provided with a pair of longitudinal channels 30, 31 for the reception of the address plate 32. This plate may be of the form shown having an arcuate intermediate region and 85 depressed edge portions under-curved on themselves for strength, and adapted to occupy the channels 30 and 31 when it is shoved endwise into place. Between these channels is a portion of the drum providing 90 a support for the intermediate portion of the plate. The plate, which is shown conventionally may if desired have raised projections like the blanket and carry similar embossed printing strips.

95

The address plates may be inserted manually or in another manner as desired, a different plate for each rotation. The prior application referred to shows a convenient mechanism enabling the manual installation 100 and removal of the address plate.

As heretofore mentioned, the paper may be fed manually or automatically as desired. The drawing illustrates at 90 and 91

a pair of feed rolls connected by gearing 93 with the platen and operating to progress the paper to the region between the drum and the platen. The drawing also shows an 5 ejector roll 95 geared with the drum and co-acting with a stripper spring 96, but these parts are shown merely incidentally.

The mechanism described enables the 10 simultaneous printing of the body and address of an addressed letter through an inking ribbon with comparative rapidity. Mechanism which I will now describe is provided to enable the envelope to be printed from the same address plate while in its position on the drum.

The envelope printing platen, designated 50 is a rotary member adjacent the drum, at the rear thereof on an axis parallel therewith and having such arcuate extent as will 20 coact with the address portion only of the address plate and not engage the salutation, should there be one on the plate. This platen 50 is normally idle but is arranged at the proper time to rotate in cooperation with 25 the address plate at the same peripheral speed. To this end, I provide the platen 50 loose on a shaft 51, and driven by a gear 52 meshing with the gear 17 on the drum. The platen is connectible for rotation with the 30 gear 52 by a single rotation clutch designated 60 as a whole.

The clutch is best shown in Fig. 3. That figure shows the gear 52 journaled on a stud 55 mounted in an extension of the end plate 35 13. One member of the clutch consists of a disk 60 rigid with this gear 52 and shown as pinned to a hub on the gear; another member consists of a disk 61 rigid with the platen; a third member comprises an intermediate disk 62 having radial ribs 63 occupying corresponding grooves in the disk 61 (after the manner of an Oldham coupling), and the final member comprises a locking pin 65 adapted to lock the members 60 and 45 62 together. This locking pin is slidably mounted in the member 60 and may engage a notch in the member 62. The clutch pin 65 is normally held withdrawn by a lever 50 110 which constitutes part of my detecting mechanism which will now be particularly described.

On the printing drum is a cam 101 (Fig. 4) which on each rotation of the drum acts on a roller 102 on the end of an arm 103 pivoted at 104 and having a depending portion 105 to which is anchored a tension spring 106. This arm has an overhanging lip 107 which bears against a compression spring 108, the other end of which bears 60 against an arm 110, also pivoted at 104. The action of the cam accordingly is to raise the roller and swing the arm 110 toward the drum if the arm is free to move, otherwise to compress the spring 108.

65 The arm 110 is normally held in the posi-

tion shown in Fig. 4 by a latch arm 120 which is a rock arm on a shaft 121 which carries another rock arm 122 constituting a detecting finger. Extending between the drum and envelope platen is a pocket 130 for the envelope to be printed, comprising a substantially vertical front plate 131 and a rear plate 132 back of the front plate, extending vertically and then curved over the top of the platen. The detector finger, when 70 no envelope is present, extends through openings 135 in the pocket as shown in Fig. 2, being held in that position by the light coiled spring 125 acting on the rock shaft 121. The finger in such position holds the 75 latch arm 120 in the position shown in Figs. 4 and 5 to prevent the action of the arm 110. Whenever an envelope is dropped into the 80 pocket, it swings the detecting finger 122 downwardly and thus rocks the latch arm 120 free from the arm 110. Under these circumstances when the cam 101 acts on the roller 102, the arm 110 is moved toward the 85 drum.

When the arm 110 is moved as just described, it is withdrawn from the clutch pin 65 and the spring 66 forces the clutch pin into action, thus locking the platen shaft 51 to the driving pinion 52 and giving the platen 50 one complete rotation to print the 90 address on the envelope.

Before the printing of the envelope is completed, the cam 101 will have cleared the roller 102 and the arm 110 will have been returned by a suitable spring to the position 100 of Figs. 3, 4 and 5, where its beveled edge 111 will engage the collar 67 on the clutch pin and thus the clutch withdraws itself from action as the rotation is completed, stopping the driving of the platen 50. The spring 106 may effect this return by means of a lip 109 on the arm 105 overhanging the front edge of the arm 110.

The platen 50 operates through a wide opening 135 in the pocket and feeds the envelope upwardly and rearwardly so that it is discharged over the portion 132 of the pocket plate. As soon as the envelope is thus lifted from the bottom of the pocket, the detector arm is free and returns by reason of the light spring on the shaft 121 to normal position, thus returning the catch 120 to hold the arm 110.

In order to stop the envelope platen immediately upon the withdrawal of the clutch pin 65 so that the platen will be in proper position for subsequent engagement, a friction brake constantly acting on the platen is provided. As shown in Figs. 1 and 3, this comprises a non-rotatable disk 70 slidably mounted on a supporting stud 80 and pressed by springs 81 against a leather washer 82 between the disk and the adjacent end of the platen. As shown in Fig. 3, the springs 81 are mounted in cavities in screws located in 125 130

an extension of the end plate 12. The brake described gives a constant friction sufficient to stop the platen immediately when the clutch pin is withdrawn, but not sufficient to

5 add any material load to the drive when the clutch is engaged.

To enable the printing pressure of the envelope platen to be readily adjusted, I may mount the shaft 51 of this platen eccentrically in the studs 55 and 80 heretofore mentioned. These studs are normally stationary, but may be turned axially to shift the axis of rotation of the shaft 51, knurled heads 85 being provided on the studs for this purpose. 10 The studs are shown as locked in place by set screws 86.

It will be seen that my paper detecting mechanism is very simple in construction, at the same time it is effective to insure the 15 action of the envelope platen at the proper time, whenever an envelope is present and prevent such action if there be no envelope. Accordingly, the complete machine may be used without reference to the envelope to 20 print addressed circular letters whenever desired; while, if an envelope is inserted in the pocket, it is printed with the address corresponding to a letter just being printed. Such envelope when discharged may drop 25 onto the corresponding letter, if desired.

Having thus described my invention, I claim:—

1. In a machine of the character described, the combination of a form for the body of 35 a letter, a changeable form for an address, a platen coacting with both forms, a second platen adapted to cooperate with the address form only, and a paper detector responsive to the presence or absence of an 40 envelope for controlling the envelope platen.

2. The combination of a bed having a body form and a changeable address form, a platen adapted to cooperate with both 45 forms, a second platen adapted to coact with the address form only, a clutch for controlling the movement of the second platen, and a paper detector responsive to the presence or absence of an envelope for controlling the clutch.

50 3. The combination with means for holding a body form and a changeable address form, of a platen adapted to coact with both forms, a second platen to coact with the address form only, said second platen being 55 normally idle, a clutch for connecting the second platen with movable driving means, mechanism operable for each cycle of operation of the machine tending to connect the clutch, and a paper detector adapted when 60 the envelope is absent to prevent the operation of the last mentioned mechanism.

4. The combination of a rotary printing drum, a segmental platen cooperable therewith, means for positioning an envelope be-

tween the platen and drum while out of 65 coaction, and mechanism adapted to be actuated by the envelope for controlling the platen.

5. The combination of a rotary printing drum, a normally idle segmental platen 70 adapted to coact therewith, a pocket for positioning an envelope between the drum and platen, and mechanism engaged by the envelope when in the pocket to cause the 75 operation of the platen.

6. The combination of a rotary printing drum, a normally idle platen, a clutch for controlling the platen, an envelope positioning pocket between the platen and drum, and mechanism extending into said pocket and 80 adapted to be actuated by the envelope for controlling the clutch.

7. The combination of a rotary printing drum, a platen adapted to coact therewith, means for supporting an envelope in substantially upright position between the 85 drum and platen, and mechanism engaged by the envelope when so supported to cause the operation of the platen.

8. The combination of a rotary printing drum, a normally idle platen cooperable therewith, a normally disconnected clutch for controlling the movement of the platen, a cam on the drum, mechanism operable thereby once on each rotation for rendering the 90 clutch active, and a paper detector adapted to prevent the operation of the clutch actuating mechanism when the paper is absent.

9. The combination of a rotary printing drum, a platen adapted to coact therewith, a 100 paper guide between the drum and platen into which an envelope may be inserted and out of which the platen and drum may feed it in the opposite direction, and means engaged by such envelope when inserted for 105 controlling the coaction of the drum and platen.

10. The combination of a rotary printing drum, a segmental platen mounted on a parallel axis about which it is adapted to rotate, 110 means for driving the platen, including a normally disconnected clutch, a paper guide extending between the drum and platen into which an envelope may be inserted, and out of which the platen and drum may feed it in the opposite direction, and means engaged by such envelope when inserted for 115 controlling the clutch.

11. The combination of a rotary printing drum, a platen adapted to coact therewith, 120 an envelope guide between the drum and platen into which the envelope may be inserted and out of which it may be fed in the opposite direction, a lever adapted to be engaged by the envelope when so inserted, and means whereby the lever controls the platen.

12. The combination of a rotary printing drum, a segmental platen adapted to coact

- therewith, means for driving the plate including a normally disconnected clutch, an envelope guide between the drum and platen into which the envelope may be inserted and 5 out of which it may be fed in the opposite direction, a lever adapted to be engaged by the envelope when so inserted, and means whereby the lever controls the release of the clutch.
- 10 13. The combination of a rotary printing drum, a segmental platen mounted on a parallel axis and normally idle, means for driving the platen including a normally disconnected clutch, a cam on the drum, mechanism operable thereby for setting the clutch, an envelope guide between the drum and platen into which an envelope may be inserted and out of which it may be fed in the opposite direction when the platen is active, a 15 lever adapted to be engaged by the envelope when in the guide, and mechanism for preventing the actuation of the clutch, said preventing mechanism being movable by said lever to idle position.
- 20 14. The combination of a rotary printing drum mounted on a horizontal axis, a rotary platen on a horizontal axis parallel with the drum axis and spaced horizontally therefrom, an upwardly opening substantially 25 vertical paper guide between the drum and platen, said guide having a support for the lower edge of an envelope inserted from above into the guide, and a means adapted to be engaged by the envelope when so inserted for controlling the platen.
- 30 15. The combination of a rotary printing drum, a segmental platen alongside of the same, an envelope pocket between the two, open above and having a support for the 35 lower edge of the envelope and having an opening through which the platen may act, a detector extending into said pocket, and
- mechanism operated by the detector for controlling the activity of the platen.
16. The combination of a rotary printing drum, a platen alongside of the same, an envelope pocket between the two, comprising two adjacent separated plates, one of which has an opening through which the platen may act, a detector extending into said pocket, and mechanism operated by the detector for controlling the activity of the platen. 45
17. The combination of a rotary printing drum mounted on a horizontal axis, a segmental platen on a horizontal axis at one side of the drum, an envelope support and guide between the two opening upwardly and extending over the platen to act as a discharge guide, a paper detecting lever 50 adapted to engage an envelope in the guide, and mechanism controlled by the lever for controlling the action of the platen. 55
18. The combination of a rotary printing drum mounted on a horizontal axis, a segmental platen on a horizontal axis at one side of the drum, an envelope pocket between the two comprising a pair of separated plates one of which curves over the platen to act as a discharge guide, said plate having an 60 opening through which the platen may act, a paper detector adapted to extend through an opening in said plate into the pocket, a clutch for controlling the rotation of the platen, mechanism operable by the rotation of the drum for periodically setting the clutch, and mechanism for preventing the 65 operation of the clutch-operating mechanism, said preventing mechanism being connected with and operated by the paper detector. 70
- 75 In testimony whereof, I hereunto affix my signature.
- 80 JOHN A. HULT.
